CLAIM

The ornamental design for a elongated level vial support for a pole, as shown and described.

DESCRIPTION

This application contains subject matter in common with co-assigned, co-pending U.S. patent application Ser. No. 11/966,441 filed simultaneously herewith and entitled Level Vial Support for a Geomatics Pole, the entire disclosure of which is hereby incorporated by reference.

FIG. 1 is a perspective view of a first embodiment of an elongate level vial support for holding a level vial and for attaching to a pole, the level vial not being shown, the level vial support being shown attached to a fragmentary portion of the pole;

FIG. 2 is a left side elevational view thereof;

FIG. 3 is a front side elevational view thereof;

FIG. 4 is a top plan view thereof;

FIG. 5 is a right side elevational view thereof;

FIG. 6 is a back side elevational view thereof; and

FIG. 7 is a bottom plan view thereof.

FIG. 8 is a perspective view of a second embodiment of an elongate level vial support for holding a level vial, a shoe, and tools (all shown in phantom) and for attaching to a pole, the level vial support being shown attached to a fragmentary portion of the pole;

FIG. 9 is a left side elevational view thereof, the elongate level vial support capable of stowing a stylus, a tail end of the stylus being shown in phantom, the shoe being shown in phantom;

FIG. 10 is a front side elevational view thereof, the shoe being shown in phantom;

FIG. 11 is a plan view thereof, the level vial shown in phantom;

FIG. 12 is a right side elevational view thereof, the elongate level vial support capable of stowing a hex wrench, a tail end of the hex wrench being shown in phantom;

FIG. 13 is a back side elevational view thereof; and,

FIG. 14 is a bottom plan view thereof.

The phantom lines in the drawings indicate environmental structure that forms no part of the claimed design.
